UNITED STATES PATENT OFFICE.

WILBER E. HUNTER, OF MORGANTOWN, WEST VIRGINIA.

DESIGN FOR AN ARTICLE OF MANUFACTURE.

49,062.

Specification for Design.

Patented May 16, 1916.

Application filed February 25, 1916. Serial No. 80,532. Term of patent 7 years.

To all whom it may concern:

Be it known that I, WILBER E. HUNTER, a citizen of the United States, and a resident of Morgantown, in the county of Monongalia and State of West Virginia, have invented a new, original, and ornamental Design to be Applied to an Article of Manufacture, of which the following is a specification, reference being had to the accompanying drawing, forming a part thereof.

The figure is a view in elevation of my design to be applied to an article of manufacture.

The design comprises a vase with handles at its sides, and with a leaf design at its bottom and feathers at its top; there being at each side of the vase a rosette, the rosettes

being connected with the vase by chains of pearls, and there being above each rosette flames, and below, a floriated pendant.

My design may be etched, stamped, printed, imprinted, embossed, or worked on, or in, or cut upon any suitable glass, china, paper, cloth, or other material, or upon any metal or any other suitable material, and may be produced on or in or attached to any desired article of manufacture.

I claim:

The ornamental design to be applied to an article of manufacture as shown and described.

WILBER E. HUNTER.
